REGENERABLE DESICCATOR

Filed Sept. 16, 1947

UNITED STATES PATENT OFFICE

2,595,306

REGENERABLE DESICCATOR

Ellsworth F. Seaman, Washington, D. C.

Application September 16, 1947, Serial No. 774,250

11 Claims. (Cl. 183—4.5)

1

My invention relates broadly to adsorbing and deodorizing units and more particularly to a construction and method of making an adsorbing and deodorizing unit which may be rejuvenated from time to time whereby the life of the unit may be extended almost indefinitely.

One of the objects of my invention is to provide a construction of adsorbing unit which may be readily manufactured inexpensively on a mass production scale and which will have a relatively long period of active life.

Another object of my invention is to provide a construction of adsorbing unit having a desiccant material built therein and associated with an electrical heating element whereby after the desiccant material has performed its function of adsorption the electrical heating element may be energized for reactivating the desiccant material.

Another object of my invention is to provide construction of adsorbing unit comprising a foraminous container for receiving beads of desiccant material which may be packed around an incandescent lamp disposed within the container whereby the desiccant material may perform its function of adsorption with respect to gases circulating through the container and subsequently the unit placed in an ordinary incandescent lamp socket and the lamp energized for subjecting the desiccant to a rejuvenating operation.

Still another object of my invention is to provide a construction of deodorizing unit comprising highly porous material and an electrically operated rejuvenating means therefor.

Still another object of my invention is to provide a method for producing adsorbing units of a construction comprising a desiccant filled foraminous container with an enclosed incandescent lamp as set forth more fully in the following specification and illustrated in the accompanying drawings in which:

Figure 1 is a cross sectional view taken through the adsorbing unit of my invention and showing the association of the desiccant material with an incandescent lamp therein; Fig. 2 is a transverse sectional view taken substantially on line 2—2 of Fig. 1; Fig. 3 is a view illustrating the several components of the adsorbing unit arranged in juxtaposition with respect to each other; Fig. 4 is a schematic view illustrating one production process by which the adsorbing unit of my invention may be manufactured, and Fig. 5 illustrates one manner in which the adsorbing unit may be suspended for use in clothes closets and the like.

My invention is directed to the construction of and method of producing a simple form of adsorbing and deodorizing unit which may be readily rejuvenated from time to time for use in a variety of ways for maintaining a dry and deodorized atmosphere in a confined space. My invention covers generally the design of an adsorbing and deodorizing unit intended for use in confined spaces such as cracker boxes and other food con-

2

ainers requiring dryness for their continued palatability, and in clothes closets, basements, and damp places. While I have illustrated my invention by reference to a small portable unit, I may apply the principles of my invention to large size units.

In operation the working cycle of the adsorbing unit consists of a period of time which may range from several days to several months during which the moisture is removed from the air and adsorbed in the adsorbing unit. When the moisture holding capacity of the unit is reached for any specified maximum relative humidity of the surrounding air the unit is screwed into a standard 110-volt lamp socket so that it may be reactivated by driving off the adsorbed moisture. It is then ready for another adsorbing period.

The adsorbing unit consists of a perforated metal container, a desiccant material and a heating element. The desiccant may consist of any of an adsorbing material such as silica gel, certain clay products, and spherical beads as manufactured by the Socony Vacuum Oil Company and designated S/V Sovabead designating silica gel in irregular, granular, or spherical grain form. It is intended in the construction set forth herein to utilize any of the materials regardless of shape but it is claimed that the utilization of the spherical shapes results in air or gas circulation performance which is new and different in its end result from that obtained from other materials, and is of greater significance than the ordinary substitution of one material for another.

The heating element may consist of wound resistor, composition resistor, resistance wire, incandescent lamp or other method of heating.

Referring to the drawings in detail reference character 1 designates a perforated metal cylindrical member having an open end 1a and a circular inwardly directed central flanged portion 1b in the other end. The perforations in the cylindrical member 1 have been represented at 2 uniformly distributed throughout the area of the cylindrical member in both of the side walls and in the flat annular end portion represented at 1c. The cylindrical member is arranged to receive an incandescent lamp which I have represented at 3. The incandescent lamp 3 contains a bulbular portion 3a and a screw plug base portion 3b. The lamp has the base portion 3b thereof introduced through the circular opening 1d in the flanged portion 1b of the cylindrical member 1 so that the inwardly directed frusto-conical shaped flange 1b has the edge 1e thereof directly contacting the glass of the bulbular portion 3a of the lamp 3.

A length of asbestos cord 4 soaked in liquid cement such as a paste of sodium-silicate and asbestos powder is then forced into the annular recess disposed between the inclined wall constituted by flange 1b and the glass wall of the bulbular portion 3a of lamp 3 and allowed to harden.

A rigid cemented joint is thus secured between cylindrical member 1 and the lamp 3. The foraminous cylindrical member 1 has the interior of the cylindrical wall thereof spaced from the bulbular portion 3a of lamp 3. The taper of the bulbular portion 3a of lamp 3 adjacent one end and the semi-spherical shape of the bulbular portion 3a at the opposite end provides a transverse zone within cylindrical member 1 which varies from a minimum radius substantially centrally of cylindrical member 1, to a maximum adjacent opposite ends of cylindrical member 1. The area within these transverse zones interiorly of cylindrical member 1 is filled with substantially spherical beads of desiccant material represented at 5. This desiccant may be silica gel, certain clay products, or beads designated as S/V Sovabeads, hereinbefore referred to, possessing moisture adsorbing properties of a high order. These substantially spherical beads are filled in around the bulbular portion 3a of lamp 3 and are packed within the transverse zones of differing radii extending from a minimum substantially centrally of cylindrical member 1 to a maximum adjacent opposite ends of cylindrical member 1.

Where the flange portion 1b of the container 1 is turned outwardly instead of inwardly the cement is applied in an annular zone around the lamp bulb and around the outwardly extending flange of the container for rigidly connecting the container to the lamp bulb.

The container for the beads of desiccant as thus prepared is then leveled off and a closure cap 6 applied to the end of cylindrical member 1. The closure cap 6 has a substantially solid annular depending skirt 6a, which may or may not be threaded, which connects with the substantially solid zone 1f of cylindrical member 1 adjacent the end 1a thereof, which may or may not be correspondingly threaded. The skirt 6a is cemented to the zone 1f for retaining the desiccant material 5 within the cylindrical member 1. The end of the closure cap 6 is perforated, as represented at 6b to facilitate the circulation of air or gases through the cylindrical side walls of cylindrical member 1, and through both ends of cylindrical member 1 in paths through the interstices between the beads of desiccant material 5.

The method of producing the adsorbing unit on a mass production scale is illustrated more clearly in Fig. 4 wherein reference character 7 designates one of the transversely journaled drums supporting a conveyor belt 8 and driven by shaft 9. The drum 7 has a substantially hexagonal periphery thereon providing a multiplicity of flat faces for receiving, supporting and propelling the flat interconnected link members 10 constituting the conveyor belt 8. The flat interconnected link members 10 form tables which are recessed at spaced intervals at 11, 12, 14, etc., for receiving the projecting screw plug bases 3b of the partially assembled lamps and associated foraminous containers 1. The projecting ends 3b of the lamps extend into the recesses 11, 12, 14, etc., and assist in maintaining the foraminous containers 1 in a vertically erect position for movement in the direction of the arrows beneath a desiccant filling station located at 15.

The desiccant filling station 15 comprises a feed hopper 16 which receives the beads of desiccant material 17 for gravitationally delivering the desiccant beads through spaced spouts 18, 19 and 20 under control of the valve cut-off member 21 which is provided with corresponding apertures

22, 23 and 24 adapted to be aligned with, or moved to misaligned position with respect to spaced spouts 18, 19 and 20. Thus, as the conveyor system progressively advances a group of foraminous containers 1 into position beneath the spouts 18, 19 and 20, the beads of desiccant material are filled into the containers. In order that the beads of desiccant material will readily flow around the obstruction offered by the bulbulous shape of the lamp 3, I provide vibrating means for subjecting the link 8' immediately beneath the filling station to continuous vibration. The vibrating mechanism may comprise plate 25 which is free to move vertically within limits defined by guides 26 and 27 which project therein. A cam member 28 rotatably mounted on shaft 29 is driven through belt 30 from shaft 9 for successively raising and lowering plate 25 and thus imparting vibratory movement to link 8'. This vibratory action serves to settle the desiccant beads within the foraminous containers 1 around the bulbous portions of lamp 3 as represented at 1'.

The overflow of beads from the containers as they pass the filling station 15 is caught in a suitable tray and preserved for return to the hopper 16. The filled drying units then progressively advance to the positions represented at 1'', in which position a coating of cement is applied to the upper annular zone 1f of the foraminous container 1 and the closure member 6 applied thereto at the position designated 6' in Fig. 4. As the conveyor system progresses, the closure member 6 is cemented upon the foraminous container in the position designated at 1''', and the completed foraminous container with the closure member 6 applied, is moved to the position 1''''. The sealed foraminous container 1 is now ready to be removed from the conveyor as a completed article.

The adsorbing unit represented in Fig. 1 is complete in itself and is ready to be placed in use. Before using the food container size adsorbing device the unit is screwed into a standard 110 volt lamp socket and is left for approximately two hours. This dries out the desiccant. The adsorbing unit is then unscrewed from the lamp socket and may be placed in a food container such as a cannister containing such foods as crackers, breakfast cereals, potato chips, pop corn, pretzels, etc., or other food that is to be kept in a crisp condition. The opening and closing of such cannisters normally introduces such moisture as may impair the crispness and edibility of the food, but with the adsorbing unit of my invention in operation the desiccant material adsorbs moisture through the perforations 2 in the container, thus maintaining the food in crisp edible condition.

60 The unit of my invention is also applicable to the preservation of chemicals and drugs requiring dry storage; and to small parts which would otherwise corrode when stored in damp places; and to powdered resin glue that is ruined when exposed to dampness.

When the adsorbing unit begins to lose its effectiveness the unit is removed from the cannister and screwed into a lamp socket for approximately two hours, as was originally done, 70 whereby the desiccant material is dried, after which the unit regains its original effectiveness. With reasonable care the adsorbing unit will last as long as the life of the incandescent lamp constituting the drying heater.

75 I have found that certain food products which

have acquired an almost soggy condition will regain their crispness in between 24 and 48 hours by use of the adsorbing unit in the cannister containing the food products. The desiccant material is non-toxic and will not injure the food. The adsorbing unit should never be immersed in water since this will ruin the desiccant material inside the perforated container. The unit, however, can be cleaned by wiping it with a damp cloth.

Where it is desired to utilize the adsorbing unit in a clothes closet and the like, I provide a suitable hanger for the unit as represented in Fig. 5. The hanger may be in the form of a flexible link chain connected at one end to the closure member 6 and at the other end to a ring-like hanger member. In Fig. 5 I have shown a rod-like member 31 connected at the end 31a to the closure 6, and connected at the end 31b to the ring-like hanger 32 by which the unit may be suspended within the clothes closet. Any suitable support for the adsorbing unit may be provided. The unit may also be supported from the floor or mounted on a shelf or other support. The position of mounting may locate lamp base vertically erect at the top of the unit with the closure 6 serving as a supporting base.

While I have indicated in the drawing that the housing or cylindrical member 1 is formed from metal I wish that it be understood that this member may be formed, molded or woven from any material which will withstand the desiccant activation temperature. Woven material includes glass cloth. The important consideration is that there be adequate provision for circulation of the moisture laden air or gases through the cylindrical member around the bulbular portion of the lamp and through the interstices between the beads of granular desiccant material.

The adsorbing unit is effective to remove moisture from air or gases and simultaneously to remove odors. In its latter capacity the unit has wide domestic application in removal of cooking and other offensive odors. When used as a deodorizer I have found that activated carbon in the form of charcoal is very effective when mixed with a quantity of desiccant for simultaneous operation as a deodorizer and an adsorber. In one application of my invention a deodorizer alone may be used and the drying element employed for rejuvenating the deodorizing material.

The use of the terms desiccant, adsorber, adsorbing and adsorption, etc., in this specification, are intended to include chemically inert, non-toxic materials which take moisture and/or odors from the air or gas without physical surface appearance of moisture, and which can be reactivated by the application of heat so that the moisture and/or odors will be driven off after which the material is restored to its original condition and is ready for reuse.

The unit of my invention is particularly useful in humid weather for maintaining constant conditions of atmosphere in confined spaces in which the unit is used.

I have found the desiccant enclosed adsorbing unit and self-contained incandescent lamp drying unit highly practical in manufacture, production and efficient in its use.

I realize that modifications may be made in the structure illustrated herein and that modified processes may be employed in the manufacture of the device, and I accordingly desire that

it be understood that no limitations upon my invention are intended other than may be imposed by the scope of the appended claims.

What I claim and desire to secure by Letters 5 Patent of the United States is as follows:

1. An adsorbing unit comprising a foraminated container of cylindrical construction with a foraminated cover closing one end thereof and a centrally apertured wall closing the other end thereof, an incandescent lamp disposed within said container having the neck thereof extending through the centrally apertured wall of said container and having the envelope of the bulbular portion thereof spaced from the interior walls of said foraminated container and the screw plug portion thereof projecting exteriorly of said container, and a filling of granular desiccant material loosely packed between the envelope of the bulbular portion of said incandescent lamp and the interior walls of said foraminated container and directly contacting the curved walls of the envelope of the bulbular portion of the lamp.

2. An adsorbing unit comprising a foraminated container of cylindrical construction with a foraminated cover closing one end thereof and a centrally apertured wall closing the other end thereof, and incandescent lamp disposed within said container having the glass neck thereof extending through the centrally apertured cover of said container and having the glass bulbular portion of the envelope thereof spaced from the interior walls of said foraminated container and the screw plug portion thereof projecting exteriorly of said container, and a filling of beads of desiccant material loosely packed between the bulbular portion of the envelope of said incandescent lamp and the interior walls of said foraminated container and directly contacting the envelope of the lamp.

3. An adsorbing unit comprising a foraminated container of cylindrical construction with a foraminated cover closing one end thereof and a centrally apertured wall closing the other end thereof, an incandescent lamp disposed within said container having the neck thereof extending through the centrally apertured cover of said container and having the bulbular portion of the envelope thereof spaced from the interior walls of said foraminated container and the screw plug portion thereof projecting exteriorly of said container, a filling of substantially spherical beads of desiccant material surrounding the bulbular portion of said incandescent lamp loosely packed in the interior of said container with the interstices between said beads forming paths for the circulation of air through said foraminated container and around the envelope of the bulbular portion of said incandescent lamp and directly contacting the curved wall of the envelope, and means for pendently suspending said container from a position remote from the screw plug portion thereof.

4. An adsorbing unit comprising a foraminated container, an incandescent lamp disposed within said container having an envelope formed in a bulbular portion spaced from the interior walls of said foraminated container and connected with a screw plug portion projecting exteriorly of said container, and a filling of substantially spherical beads of desiccant material surrounding the bulbular portion of the envelope of said incandescent lamp and comprising a granular packing filling the interior of said container and forming zones of moisture adsorbing means

directly contacting the curved envelope of the lamp and having a minimum radius substantially centrally of said container and increasing in radius toward each of the opposite ends of said container.

5. An adsorbing unit comprising a container of cylindrical construction with a foraminated cover closing one end thereof and a flat end wall at the other end thereof, said end wall having a centrally disposed flanged recess therein with 10 a frusto-conical portion extending inwardly therefrom and terminating in an annular edge portion, an incandescent lamp having an envelope formed in a bulbular portion and connected with a screw plug portion, with the screw 15 plug portion projecting outwardly from said container through the centrally disposed recess therein, a cementitious material securing said bulbular portion of the envelope of said lamp to the annular edge portion of the flanged recess in said flat end wall of said container and a filling of desiccant material directly contacting and surrounding the bulbular portion of the envelope of said incandescent lamp and disposed within said container, the wall of said container being perforated for the circulation of air and gases through said desiccant material.

6. An adsorbing unit comprising a container having an end wall with a centrally disposed flanged recess therein with a frusto-conical portion extending inwardly therefrom and terminating in an annular edge portion, an incandescent lamp having an envelope formed in a bulbular portion and connected with a screw plug portion with the screw plug portion projecting outwardly from said container through the centrally disposed recess therein, an asbestos gasket disposed within the frusto-conical portion of said recess and cemented to both the bulbular portion of the envelope of said lamp and the annular edge portion of the recess in said container, a filling of desiccant beads in said container surrounding and in contact with the bulbular portion of the envelope of said lamp, and an attachable cover for said container, said container, said end wall and said cover having perforations therein for the circulation of air and gases through the interstices between said desiccant beads.

7. An adsorbing unit comprising a foraminated container of cylindrical construction with a foraminated cover closing one end thereof and a centrally apertured wall closing the other end thereof, an incandescent lamp disposed within said container having the neck thereof extending through the centrally apertured wall of said container and having the envelope of the bulbular portion thereof spaced from the interior walls of said foraminated container and the screw plug portion thereof projecting exteriorly of said container, a filling of desiccant material disposed between the interior foraminated walls of said container and the envelope of the bulbular portion of said lamp and in contacting relation with the envelope of the bulbular portion of the lamp, and a hanger attached to said container for pendently suspending said container in a position for permitting the free circulation of air through said foraminated container and through the desiccant material therein.

8. An adsorbing unit comprising a foraminated container of cylindrical construction with a foraminated cover closing one end thereof and a centrally apertured wall closing the other end thereof, an incandescent lamp disposed within 75 the container having the neck thereof extending

through the centrally apertured wall of said container and having the envelope of the bulbular portion thereof spaced from the interior walls of said foraminated container and the connecting means therefor projecting exteriorly of said container, and a filling of desiccant material interposed between the envelope of the bulbular portion of the lamp and the interior foraminated walls of said container and directly contacting the envelope of the lamp.

9. An adsorbing unit comprising a foraminated container of cylindrical construction with a foraminated cover closing one end thereof and a centrally apertured wall closing the other end thereof, an incandescent lamp disposed within the container having the neck thereof extending through the centrally apertured wall of said container and having the envelope of the bulbular portion thereof spaced from the interior walls of said foraminated container and the connecting means therefor projecting exteriorly of said container, and a filling of moisture adsorbing and deodorizing material interposed between the envelope of the bulbular portion of the lamp and the interior foraminated walls of said container and directly contacting the envelope of the lamp.

10. An adsorbing unit comprising a foraminated container of cylindrical construction with a foraminated cover closing one end thereof and a centrally apertured wall closing the other end thereof, an incandescent lamp disposed within the container having the neck thereof extending through the centrally apertured wall of said container and having the envelope of the bulbular portion thereof spaced from the interior walls of said foraminated container and the connecting means therefor projecting exteriorly of said container, and a filling of a mixture of a granulated deodorizing material and beads of desiccant material interposed between the envelope of the bulbular portion of the lamp and the interior foraminated walls of said container and directly contacting the envelope of the lamp.

11. An adsorbing unit comprising a foraminated container of cylindrical construction with a foraminated cover closing one end thereof and a centrally apertured wall closing the other end thereof, an incandescent lamp disposed within the container having the neck thereof extending through the centrally apertured wall of said container and having the envelope of the bulbular portion thereof spaced from the interior walls of said foraminated container and the connecting means therefor projecting exteriorly of said container, and a filling of deodorizing material interposed between the envelope of the bulbular portion of the lamp and the interior foraminated walls of said container and directly contacting the wall of the envelope of the lamp.
